UNITED STATES PATENT OFFICE.

FREDERICK R. PARKER, OF CHICAGO, ILLINOIS.

DESIGN FOR A TOBACCO-PIPE.

56,564.

specification for Design.

Patented Nov. 9, 1920.

Application filed January 26, 1918. Serial No. 214,026. Term of patent 14 years.

To all whom it may concern:

Be it known that I, FREDERICK R. PARKER, a citizen of the United States of America, residing at Chicago, in the county of Cook and State of Illinois, have invented a new, original, and ornamental Design for Tobacco-Pipes, of which the following is a specification, reference being had to the accompanying drawing, forming a part thereof and illustrating the invention.

The figure of the drawing is a side elevation of my new design for tobacco pipes, which design consists essentially of the representation of a human leg, foot and thigh, preferably bent to the position shown. The foot of the figure is the mouth-piece of the pipe, the leg of the figure is the stem of the

pipe, and the thigh of the figure is the bowl of the pipe.

I may make my tobacco pipe of various shades and colors, and may decorate it in various manners, without departing from the invention.

I claim:

The ornamental design for a tobacco pipe substantially as shown and described.

As inventor of the foregoing I hereunto subscribe my name, this 22nd day of January, 1918.

FREDERICK R. PARKER.
